Primary Examiner — Janice Patyk*Assistant Examiner* — Kendra L Hebel*(74) Attorney, Agent, or Firm* — Ross Brandborg(57) **CLAIM**

The ornamental design for a coffee pod organizer, as shown and described.

DESCRIPTION

FIG. 1 is a front perspective view of a coffee pod organizer showing my new design;

FIG. 2 is a rear perspective view thereof;

FIG. 3 is a top plan view thereof;

FIG. 4 is a top plan view thereof, shown in alternate configuration;

FIG. 5 is a bottom plan view thereof, shown in alternate configuration;

FIG. 6 is a bottom plan view thereof;

FIG. 7 is a side elevation view thereof;

FIG. 8 is a front elevation view thereof; and,

FIG. 9 is an exploded front elevation view thereof.

The broken lines in the drawings show portions of a coffee pod organizer and form no part of the claimed design.
